(57) **CLAIM**

The design for an insert for a door seal assembly, as shown and described.

DESCRIPTION

FIG. 1 is a perspective view from below, to the front and to one side of the new design for an insert for a door seal assembly;

FIG. 2 is a front view thereof, with a rear view being identical thereto;

FIG. 3 is a left side view thereof, with a right side view being identical thereto;

FIG. 4 is a top view thereof; and,

FIG. 5 is a bottom view thereof.

In the drawings, the broken lines depict environmental subject matter only and form no part of the claimed design, and the break lines depict the bounds of the Claim. The area between the break lines forms no part of the claimed design.
